(57) **CLAIM**

The ornamental design for a set of levers, as shown and described.

DESCRIPTION

FIG. 1 is a front perspective view of a set of levers showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of the circular regions on the rear of the levers and the bottom surface of the levers form no part of the claimed design.
